UNITED STATES PATENT OFFICE

LOUIS V. ARONSON, OF NEWARK, NEW JERSEY.

DESIGN FOR A CLOCK-CASE.

SPECIFICATION forming part of Design No. 35,817, dated March 18, 1902.

Application filed February 24, 1902. Serial No. 95,488. Term of patent 3½ years.

To all whom it may concern:

Be it known that I, LOUIS V. ARONSON, a citizen of the United States, residing at Newark, in the county of Essex and State of New Jersey, have invented and produced a new and original Design for a Clock-Case, of which the following is a specification, reference being had to the accompanying drawings, forming part thereof.

10 Figure 1 is a front elevation of a clock-case embodying my new design. Fig. 2 is a side elevation of the same.

As shown in the accompanying drawings, the leading or material features of my design 15 are the ornamental base with scroll feet, the cupid standing thereon, the fluted columns supporting the clock-socket, and the clock-socket encircled with scrolls and having an upwardly-projecting scroll extended above 20 the socket.

This design comprises an ornamental base 25 *a*, provided with scroll feet, with a naked figure of a cupid *b* standing thereon, the left hand of the cupid being extended and supporting a mandolin and the right hand in an operative position on the strings of said man-

dolin. The right leg of the cupid is drawn back, and feathery wings project from the shoulder-blades of said cupid. The ornamental base *a* is provided near its edges with 30 two fluted columns *c*, having fancy scroll capitals, and the socket *d* for the clock disposed between the fancy scroll capitals of the fluted columns above the cupid, the casting of the socket for the clock being encircled with scrolls which are formed integral with the fancy scroll capitals of the columns. Light flying drapery surrounds the cupid's 35 waist, and the whole design is in the colonial style of the seventeenth century. 40

Having thus described my invention, what I claim is—

The design for a clock-case as herein shown and described.

Signed at Newark, in the county of Essex 45 and State of New Jersey, this 17th day of February, 1902.

LOUIS V. ARONSON.
